UNITED STATES PATENT OFFICE.

NICHOLAS VANDERHORST, OF LONDON, ENGLAND, ASSIGNOR TO HERMAN LINDARS,
OF LONDON, ENGLAND.

LOCOMOTIVE-VALVE GEAR.

Application filed March 11, 1927. Serial No. 174,571.

This invention relates to counterflow locomotive steam engines of the type employing steam distribution valves other than the usual piston or slide valves, more particularly to the valve gear of such engines.

In modern locomotive practice the tendency is to use steam both of high pressure and high degree of superheat, and considerable difficulties have been met when, for example, the ordinary long travel slide or piston valve is used under such conditions. To obviate the comparatively long travel and large wearing surfaces needed by slide or piston valves controlling, for example, live and exhaust steam ports for both ends of the cylinder and requiring considerable lubrication, it has been proposed to use short travel poppet or like valves each pair of same controlling the steam events on one side of the piston. Such valves, however, have, like the long travel valves, been used in a casing or plurality of casings cast integrally with the cylinder body thus necessitating the said cylinder casting being of complicated or irregular design and very difficult to cast, particularly as such cylinders for working with high pressure and superheated steam have to be made of cast steel.

The intricate cylinder casting as above is at all times in direct contact at one or more regions with the live steam and the risks of breakages due to the unavoidable and uneven expansion are very great.

The clearance volumes should be kept to a minimum for efficient working and the passageways traversed by the steam, should be short and as far as possible free from abrupt corners.

Space being a serious consideration in locomotive practice access to the valves and ease of withdrawal thereof for inspection, cleaning or other purposes are important requirements as is also the accessible arrangement under running conditions of the mechanism for actuating the valves, which mechanism, further, should not require to be disturbed or dismantled when effecting such inspection and/or removal of the valves.

The object of the invention is to embody the foregoing desirable features to the exclusion of the foregoing disadvantages and in general to provide an improved valve gear, using short travel valves and a cyl-

inder of simplified and cheapened construction on which are cast only such parts as are necessary to secure it to the locomotive frame and, if required, to carry the valve actuating mechanism.

In carrying my invention into effect, the valves are arranged in housings cast integrally with the detachable cylinder end covers, and are further preferably all arranged in such a way as to allow of their being actuated from above, and of easy accessibility for inspection and cleaning purposes, which are so essential in locomotive practice where space is a serious consideration.

In order that my invention may be understood drawings are appended, in which:

Figure 1 is a fragmentary vertical longitudinal section in a plane parallel with the cylinder axis and including the centre line of the steam inlet valve at one end;

Figure 2 is a similar view to Figure 1 on a plane including the centre line of the exhaust valve;

Figure 3 is a vertical section on a plane including the centre lines of both valves, that is, normal to the cylinder axis;

Figure 4 shows an outside view in perspective of the cylinder casting with the end covers removed showing the simple construction thereof permitted by the present invention.

Referring, now, to Figure 3, the valves *a*, *b* are arranged in housings in a casting *c* of the shape shown which is formed integrally with the cylinder end cover flange *d*. A similar casting and valve arrangement is provided at the other end of the cylinder, but reversed left for right, one only being hereinafter described, the description applying equally to both. The valves are disposed symmetrically one on each side of a vertical plane including the centre line of the cylinder as shown and are provided with seatings *e*, *e*₁ formed by the openings *f*, *f*₁ in the horizontal partitions in the housings. The valve heads are carried on spindles *g*, *g*₁, which can be axially moved within guides *h*, *h*₁ respectively. These guides may be of brass, gun metal or other material and are arranged with their centres parallel to one another and at right angles to the cylinder axis, being a firm and preferably slightly tapered fit from the interior of the valve housing through the extensions or bosses *i*, *i*₁ above the latter.

110

With the valves shown a second seating is provided for each by the lower surfaces of the flanges h_2 , h_3 of the guides, the upper surfaces of said flanges forming abutments between the guides and the inner sides of the respective housings.

The upper end of each valve spindle carries a spring cap j which retains in position a compression spring k surrounding the 10 spindle g and bearing at its lower end against the top of the boss i . As shown in Figure 1, live steam is admitted by the pipe l into the outer passage m below the valve a . On exerting downward pressure on the 15 spindle g against resistance of the spring k the valve a is lowered from its seatings and steam is allowed to pass through the opening f and by way of the passage n into the cylinder o , where it acts upon the piston p . 20 The exhaust valve operates in a similar manner. As shown in Figure 2 exhaust steam from the cylinder space passes into the space m_1 below and on the inner side of the valve b and, when the latter is opened 25 against the spring k_1 , the steam passes through the opening f_1 into the space n_1 . The steam is then conducted away by means of the elbow pipes or bends q , q_1 , as shown in Figures 3 and 4, to the funnel, for example 30 through the passage q_2 , q_2 in the bracket z of the cylinder.

The valves may be actuated by any means preferably such as will not necessitate the various steam and exhaust events for either 35 or both ends being mutually dependent. The separate cam arrangement for each valve as shown in Figure 1, is, however, preferred. The cam r is carried upon the shaft r_1 situated transversely of the cylinder and rotatably mounted conveniently on the brackets 40 r_2 secured to the top of the pad x cast on the cylinder top. Rotation of the cam causes the push rod s to reciprocate in its guides t , t_1 , a roller s_1 being preferably provided for reducing friction. At its other end the push 45 rod thrusts against one arm of a bell-crank lever u which is swivelably carried on a horizontal transverse pivot u_1 secured to or cast integrally with the flange d . The other arm 50 of the bell-crank u is provided with adjusting means, such as a screw, v , the lower end of which bears upon the upper end w of the valve spindle. The shape of the cam can be 55 such that in rotating at a uniform angular velocity it actuates the valve as desired through the intermediary of the gear above described. The screw v allows of adjustment and the taking up of wear and tear.

In all cases the valves are situated as close 60 as possible to the cylinder and sharp bends and other such obstructions to the even flow of steam are avoided, which makes the invention particularly suitable for use in, for example, high speed or passenger locomotives, and it will be seen the parts of the

cylinder cover and valve housings which are subjected to high pressure and high temperature are of a simple design and thus constitute an improvement in that the invention overcomes the disadvantages hereinbefore indicated. 70

In addition it will be seen that the live and exhaust steam cavities m , m_1 , respectively are so arranged as to reduce as far as possible the clearance volumes behind the piston. 75

Accessibility to the valves and housings is provided for by the circular openings y , y_1 , concentric with and below the valves. These openings are such as to allow the valves to pass through. The only work necessary is to remove the flanges which normally cover said openings and, after detaching the spring caps, j , j_1 from the respective valve spindles, pull the valves out together with their spindles. The guides h , h_1 as distinct 80 from known practice are adapted to be undisturbed by the above procedure and to remain in position, being tightly fitted in the upper parts of the housings. The design, however, also permits of withdrawing said 85 guides readily if desired. The valve actuating mechanisms it is to be noted, in the arrangement shown in the drawings, likewise do not require to be disturbed, and being all arranged above the cylinder or valve 90 housings are themselves easily accessible for adjustment or the like.

It is to be understood that modifications and additions may be made to the foregoing construction without departing from the 100 spirit of the invention as set out in my appended claims.

Having now described my invention, what I claim as new and desire to secure by Letters Patent is:—

1. In a double acting counterflow locomotive steam engine having a pair of poppet valves for each end, the combination with a substantially plain non-ported steam cylinder and means for securing same in a 110 substantially horizontal position to the locomotive frame, of separate end covers for said cylinder each of said covers having cast thereon in close communication with the respective end of said cylinder, housings 115 for one pair of said valves adapted to carry said pair of valves in an inverted position substantially symmetrically one on each side of a vertical plane containing the cylinder axis with their axes of displacement 120 substantially normal to a horizontal axial plane, and said valves each being operable from one and the same side of said last-mentioned plane and accessible and removable from the other side of the latter. 125

2. The combination according to claim 1 having a balanced poppet valve in each housing, an upwardly extending spindle connected to each valve, guiding means for each spindle in the respective housing and extend- 130

ing upwardly through the top thereof, a pair of inverted seatings in each housing for each valve, resilient means externally of said housings adapted to hold said valves upwardly against their respective seatings, 5 mechanical means externally of and above said cylinder for independently actuating said valves and adapted to open same by downward thrust upon the spindles thereof, 10 and means for withdrawing said valves from said housings from below the latter without disturbing the said seatings spindle guides and actuating mechanism.

3. The combination claimed in claim 1 having a pair of isolated valve housings cast 15 side by side on the outer face of each of said covers, a vertically operative balanced two face valve and horizontally superposed double seatings therefor in each housing, 20 spindles attached to said valves and extending upwardly through apertures in the tops of said housings, guides for said valve spindles each providing the upper seating for the respective valve and extending upwardly with said spindles, steam passages 25 in said housings, ports in each cover connecting the interior of the cylinder with each of said pair of housings respectively above and below the valves therein, resilient means externally of the housings acting 30 axially upon the valve spindles and holding the valves upwardly against said seatings, and mechanical means disposed above said valves for displacing the latter from said seatings against said resilient 35 means.

4. The combination claimed in claim 1 having a pair of isolated valve housings cast side by side on the exterior of each of 40 said covers on opposite sides of the cylinder axis, a horizontal partition in each housing, an inverted balanced poppet valve in said housing vertically movable within a circular opening in said partition, the 45 under side of which is adapted to form the lower one of two superposed seatings, a spindle coaxially connected to and extending above said valve and through the top of said housing, a guide surrounding said spindle

passing firmly through an aperture in the upper side of said housing and having a flange at its lower end within said housing, 50 said flange forming the upper one of said seatings, means for admitting live steam to one of the housings in each end cover 55 below the circular opening therein, ports through said cover for admitting said steam from the upper side of said partition to the interior of the cylinder, like ports for admitting exhaust steam from said cylinder 60 to the lower side of the opening in the partition in said other housing, a compression spring encircling the valve spindle externally of the housing for holding each of 65 said valves upwardly against their respective seatings, separate cam actuated means carried on said covers for moving each of said valves and opening them from above against the action of said spring means, and openings in the bottom of each housing for 70 removing said valves and valve spindles independently of the guides and without disturbing said cam means.

5. In a locomotive having a horizontally disposed steam cylinder and a pair of poppet valves for each end thereof, the combination with a substantially plain non-ported cylinder, of a detachable cover for each end thereof, said cover having two ports from its cylinder-engaging face respectively to the insides of two isolated valve housings cast side by side on a horizontal diameter integrally on its external face, an inverted balanced poppet valve and seatings therefor in each housing and closely adjacent to said external face, a spindle connected to each valve and extending therefrom through guiding means penetrating the respective housing, external resilient means adapted to hold said valves against 80 said seatings, and independently actuated transmission means for each valve externally of said housings and operatively connected to the respective valve spindles.

In testimony whereof I have signed my name to this specification.

NICHOLAS VANDERHORST.
